The ornamental design for a dispensing cap, as shown and described.

DESCRIPTION

FIG. 1 is a perspective view of a dispensing cap in accordance with my new design;

FIG. 2 is a top plan view thereof, shown at an enlarged scale;

FIG. 3 is a front elevation view thereof;

FIG. 4 is a right side view thereof, the left side view being substantially identical thereto;

FIG. 5 is a rear elevation view thereof; and

FIG. 6 is a bottom plan view thereof;

FIG. 7 is a perspective view of a dispensing cap in accordance with a second embodiment of my new design;

FIG. 8 is a top plan view thereof, shown at an enlarged scale;

FIG. 9 is a front elevation view thereof;

FIG. 10 is a right side view thereof, the left side being substantially identical;

FIG. 11 is a rear elevation view thereof; and,

FIG. 12 is a bottom plan view thereof.

The containers illustrated in phantom in FIGS. 1 and 7 are merely intended to show my new dispensing cap in its intended environment and otherwise form no part of the claimed subject matter.
